UNITED STATES PATENT OFFICE.

GUSTAV F. W. SCHULTZE, OF OAKLAND, CALIFORNIA.

COMBINED VENDING-MACHINE AND GAME APPARATUS.

1,298,800.

Specification of Letters Patent.

Patented Apr. 1, 1919.

Application filed March 19, 1918. Serial No. 223,278.

To all whom it may concern:

Be it known that I, GUSTAV F. W. SCHULTZE, a citizen of the United States, residing at Oakland, in the county of Alameda and State of California, have invented 5 certain new and useful Improvements in Combined Vending-Machines and Game Apparatus, of which the following is a specification.

10 This invention relates to a combined vending device and amusement apparatus wherein in the purchasing coin or token deposited in the vending apparatus is capable of being projected or catapulted toward a target and 15 if a certain score is made the token is returned, the merchandise being obtained free, otherwise the token is retained in the apparatus.

15 The principal object of the invention is to 20 provide a device wherein the skill or marksman ship of the purchaser in shooting the deposited coin or token controls the final disposal of said coin or token, whereby a skilled marksman is enabled to obtain the merchandise dispensed by the vending apparatus and 25 is also enabled, due to his good marksman ship, to obtain the return of said purchasing coin or token.

With the above mentioned and other objects in view, the invention consists in the 30 novel construction and combination of parts hereinafter described, illustrated in the accompanying drawings and pointed out in the claim hereto appended; it being understood 35 that various changes in the form, proportion, size and minor details of construction within the scope of the claim may be resorted to without departing from the spirit or sacrificing any of the advantages of 40 the invention.

To more fully comprehend the invention, reference should be had to the accompanying 45 sheets of drawings, wherein—

Figure 1 is a view in front elevation of 50 the preferred embodiment of my invention.

Fig. 2 is a vertical sectional view taken on line 2—2 of Fig. 1, viewed in the direction of the arrows.

Fig. 3 is a vertical sectional view taken on 55 line 3—3 of Fig. 2, and viewed in the direction of the arrows.

Fig. 4 is a vertical sectional view taken on line 4—4 of Fig. 1 viewed in the direction of the arrows, and illustrating the coin or

token slot and the merchandise vending apparatus.

Fig. 5 is a sectional view taken on line 5—5 of Fig. 4, disclosing the laterally disposed slot for conveying the purchasing coin or token to the shooting apparatus.

Fig. 6 is a view in detail, taken on line 6—6 of Fig. 5.

Fig. 7 is a sectional view taken on line 7—7 of Fig. 3, illustrating the mechanism for returning the purchasing coin or token 65 after a proper score is made therewith.

Fig. 8 is a longitudinal sectional view of the preferred form of shooting apparatus.

Fig. 9 is a sectional view taken on line 9—9 of Fig. 8.

Referring more particularly to the several views of the drawings, wherein like characters of reference designate corresponding parts, the reference numeral 1 indicates the front wall; 2 the side walls; 3 the top wall; 4 the bottom wall and 5 the rear wall, forming a suitable housing or casing, the upper portion of one side, the front wall and the top wall being preferably of glass, as indicated at 6. At one side of the 75 chamber is formed a suitable merchandise or article holding casing 7 adapted preferably for the containing of gum, chocolate or the like, which articles are positioned therein in superimposed relation within a 80 guide 8.

A slide gate 9 having an operating handle 10 extending exteriorly of the front wall, controls the dispensing of the merchandise, and said gate is provided with a recess 11 normally lying beneath the guide 8 and of a sufficient depth and size to enable a single article to be dispensed. The gate slides on a suitable plate 12 having an aperture 13 for registering with the recess 11 on the inward 95 manual depression of the gate 9. Thus on each inward manual movement of the gate 9, the article to be dispensed, and contained within the recess 11, drops from the slide gate 9 through the opening 13 into a suitable 100 discharge chute 14, terminating at its outer end in a cup 15.

The operation of the slide gate 9 is controlled by the depositing of a controlling coin or token within the upper end of a 105 vertically disposed slot or guide 16. Positioned within the slot or guide 16 is a lever 17 fulcrumed within its length, as at 18, and

carrying at its rear end a weight 19 which is sufficient to normally maintain the free end of said lever raised, but is capable of being overbalanced by the weight of the controlling coin or token.

Depending from and fulcrumed at its upper end to the lever 17 is a controlling rod 20, the lower curved end 21 of which is adapted when the lever lies in its normal position, as in Fig. 4, to be received in an alined opening 22 formed in the plate 12 and slide gate 9, thereby precluding inward movement of the slide gate. On the depressing of the free end of the lever by the weight of the operating coin or token, said curved end 21 is released from the opening 22, and said lever is maintained in a downwardly inclined position by a suitable pivotally mounted latch 23, which is adapted to overlie the free end of said lever 17. When in this position the slide gate 9 is capable of inward movement to dispense the merchandise, the delivery of which is controlled thereby.

25 The slide gate 9 carries a laterally disposed lug 24 which is adapted on the inward movement of said slide gate to contact with the lower end of a trip member 25 fulcrumed as at 26 adjacent its upper end, and the extreme upper end of which is adapted for engaging the bent end 27 of the latch 23 when the same is in a perpendicular position to force the same from contact with the upper surface of the free bent end 28 of the lever 17.

30 This operation permits the weight 19 to draw the bevel end 29 of the bent portion 21 of the rod 20 to contact with the undersurface of the slide gate 9, and on the outward or return movement of said slide gate by the spring 30, said beveled end 29 engages the rack 31 on the underside of the slide gate 9 and prevents the second inward movement of the same during the return outward movement of the slide gate by the spring 30.

45 On the completion of the outward movement of the slide gate by the spring 30, the curved portion 21 of the rod 20 is again received in the opening 22 in the slide gate 50 and locks the same until the deposit of another controlling token or coin.

55 Positioned in proximity to the lower end of the slotted coin or token receiving guide 16 is the upper end of another coin or token receiving guide 32 which is adapted to receive the coin immediately after the same depresses the free end of the lever 17, said guide conveying the coin or token at a downward inclination and delivering the same 60 into an inlet opening 33 in the upper surface of a suitable projecting device 34, illustrated in the form of a pistol. The pistol is provided with a suitable slot 35 in the barrel 36 thereof, and is also provided with a hammer 65 37 pivoted as at 38 and formed with an in-

tegral trigger 39, the firing pin 40 of the hammer adapted to extend through an opening 41 in the rear downwardly curved portion of the barrel slot 35.

A controlling spring 42, the tension of which is capable of being varied by any suitable means, as by the adjusting screw 43, is received at its free end in a recess 44 in the hammer 37 adjacent the fulcrum point thereof, said spring being designed to either 75 retain the hammer in cocked position or to exert pressure on the hammer when it is desired to move the same on its fulcrum by pressure on the trigger to discharge the coin or token from the curved inner end thereof. 80

As in dotted lines, Fig. 9, the coin or token projecting pistol normally lies with the butt 45 thereof in substantial alinement with the discharge end of the receiving guide 32 to position the opening 33 in the 85 barrel in register therewith; this being accomplished by the weighted arm 46 extending laterally from the barrel. The barrel is provided with a substantial spherical portion 47 mounted in the fulcrum 48 within 90 the front wall 1, the muzzle of the barrel extending within the casing and the butt thereof lying without the said casing, thereby enabling the operator, after the reception of the coin or token within the slot 35, to 95 aim the pistol toward the target, hereinafter described.

In spaced relation in front of the rear wall 5 is a false wall 49 provided with a suitable target 50 on the face thereof, said target being provided with a slotted opening 51 through which the controlling coin or token as discharged from the pistol may pass, provided the pistol is properly aimed.

100 The tokens or coins striking the wall 49 and not passing through the opening 51 in the target thereon drop in front of said wall and pass through the opening 52 into a suitable receptacle or chamber 53. The tokens or coins passing through the opening 51 are 105 received within a trough 54 pivotally mounted as at 55, at a point below the opening 51 within the chamber 56, said trough preferably provided at one end with a signal device 57, the one illustrated being in the form 110 of a flag, and said trough is adapted on the reception of a coin or token to pivot on its fulcrum point 55 and to assume a position as in Fig. 3 of the drawings, raising the signal or flag above the false wall 49, indicating to 115 the marksman that a bull's-eye has been made. On the pivoting of the trough the coin or token received therein will slide toward the discharge end 58 thereof, but will be precluded from passing therefrom into a 120 discharge chute 59 extending to the front of the casing by a suitable arm 60 adapted to lie within the path of the discharge end 58 of the trough 54. On the movement of said arm 60 from the discharge end 58 of the 125 130

trough 54 by the operator grasping the outer end 61 thereof which projects in front of the casing, the coin or token will be released from the trough 54 and be returned to the operator, thus the operator will have obtained the merchandise free, the coin having passed through the slot 51, due to his expert marksmanship, and returned in the slot 59.

To prevent the operator from clogging or 10 jamming the coin or token projecting device by depositing therein a number of tokens or controlling coins in such manner as to position a coin to pass through the opening 33 and to remain in the discharge end of the 15 guide 32, said guide is provided in its under-face, adjacent its lower end, with a cutout or opening 62 of a size sufficient to permit the dropping of a coin therethrough. On the registering of the slot 33 with the lower end 20 of the guide 32, the coins passing through said guide travel at sufficient speed to jump the cutout 62 and pass into the slot 35 through the opening 33. However, should said opening be closed, due to the reception 25 of a number of tokens in the slot 35, or should a solid portion of the pistol register with the lower end of the slot 32, the movement of the coins or tokens will be arrested at the lower end of said slot 32 and said coins 30 will pass through the opening 62.

By my present apparatus I have provided a combined amusement device with a vending machine or apparatus and after the merchandise has been obtained, the operator, if 35 he so desires, may test his marksmanship by

projecting the coin or token by which the merchandise was obtained, and if the coin or token is projected through the slot 51, the same is returned, thus the merchandise is obtained free. However, if the coin or token 40 does not pass through the opening 51, said coin is retained in the apparatus in payment of the purchase price of the merchandise.

Having thus described my invention what 45 I claim is:—

A coin or token controlled vending apparatus including an article dispensing mechanism, a coin or token receiving runway co-operating therewith, means operated by a depositing coin or token within said runway 50 for releasing said dispensing mechanism to permit the operation thereof, a plurality of coin or token disposal runways spaced from the discharge end of said coin or token receiving runway, one terminating exteriorly 55 of the apparatus and another interiorly of the apparatus, and means associated with the receiving runway and under the control of the operator of the apparatus for receiving the controlling coin or token discharged 60 from said receiving runway and for projecting the same to one of said discharge runways.

In testimony whereof I have signed my name to this specification in the presence of 65 a subscribing witness.

GUSTAV F. W. SCHULTZE.

Witness:

D. B. RICHARDS.
